UNITED STATES PATENT OFFICE.

PETER CODINA, OF JERSEY CITY, NEW JERSEY, ASSIGNOR TO THE DAUBER-SWAB CO., INC., OF JERSEY CITY, NEW JERSEY, A CORPORATION OF NEW JERSEY.

SWAB-FORMING MACHINE.

Application filed January 24, 1923. Serial No. 614,645.

The object of this invention is to provide a machine for making swabs or daubers for applying liquid polish to foot-wear, of the type used as stoppers for bottles containing the liquid, but it is to be understood that the invention is not limited to the manufacture of swabs or daubers for the one specific use mentioned.

So far as this particular machine is concerned, it operates upon wires of the proper length to form a handle or part of a handle, bends one end of them about a strand of filamentous material, and then cuts the filamentous material between adjacent wires, so that each wire is supplied with a tuft of the filamentous material which in use carries a charge or supply of the liquid to be applied.

The invention consists of a machine having a wire carrier moving past a filament feeder and in conjunction with a twisting head which twists an end of the wire about the filament, whence the thus assembled parts are presented to a wire clenching element, and then to a cutter which severs the filament for each wire, after which the thus finished device is discharged, as I will proceed to explain and finally claim.

In the accompanying drawings illustrating the invention, in the several figures of which like parts are similarly designated, Figure 1 is a top plan view of a machine serving to illustrate one form of the invention. Fig. 2 is a side elevation. Fig. 3 is an end elevation looking from the left of Fig. 2. Fig. 4 is a sectional elevation on a larger scale taken on the irregular line 4—4 of Fig. 1. Fig. 5 is a fragmentary sectional elevation showing the feed mechanism for the wire carrier. Fig. 6 is a fragmentary elevation of parts of the mechanism shown in Fig. 4, but looking from the opposite side and serving to illustrate the cutting operation. Fig. 7 is a sectional elevation illustrating the means for completing the union of the wire and tuft. Fig. 8 is an elevation of part of the wire carrier. Fig. 9 is a section taken on the line 9—9 of Fig. 8. Fig. 10 is a perspective view on a larger scale of the twister head, and Fig. 11 is a longitudinal section thereof. Fig. 12 is an elevation showing the filament in section and the wire twisted about it, and Fig. 13 is a similar view with the twisted wire flattened or clenched. Fig. 14 is an elevation of the finished swab or dauber. Fig. 15 is a side elevation of one of the guide clips.

Fig. 16 is a rear view of the twister head showing the first operation of applying the swab or dauber wire to the tuft material. Fig. 17 is a similar view showing the first wire bending operation. Fig. 18 is a similar view 60 showing the final wire bending operation. Fig. 19 is a side elevation of the twister head. Fig. 20 is a longitudinal section of the twister head with the wire bent and coiled about the tuft material.

65

The article made.

The material from which the tuft of the swab or dauber is formed may be a sliver or roving of wool or other suitable filamentous 70 or fibrous material, although the invention is not limited in this respect; but the invention will be explained here on the basis of the use of the material in strip form to which the wires are applied, and then the strip 75 severed into individual tufts or pieces. Nor is it necessary that the swab or dauber should be made of filamentous material since obviously it might be made of absorbent material in felted form or any other suitable form.

The wires, in the present illustration, are first cut to proper length and hand-fed to the machine, and by the machine the tuft and wires are united and the swab or dauber finished ready to receive any suitable handle, 85 such as a cork or bottle stopper.

In Fig. 12 is shown a tuft *a* with the wire *b* twisted about it, as shown at *c* and in Fig. 13 the wire is shown as flattened, clenched or compressed about the tuft. In Fig. 14 the 90 tuft is shown as expanded into ball form with the wire enclosed therein, and at its opposite end this wire is embedded in a bottle stopper *d* of cork, having a wooden cap *e* cemented or otherwise applied thereto and serving as a 95 handle for use in applying the liquid absorbed by the tuft.

The wire carrier.

1 is a table, suitably supported on legs 2. 100 3 is a wire carrier, mounted on a shaft 52 which is supported in bearings 73 and 133, Fig. 1, mounted on the table 1 and in a bearing 91 mounted in a cross-piece 77 of a frame including the beams 74 and 78 extending laterally from the table and bolted thereto, this cross-piece 77 being bolted to the beams 74 and 78. This wire carrier is a circular, spoked structure, having a rim 300 provided with a central groove 301 flanked on either 105 110

side by the toothed flanges 302 and 303, and the toothed flange 303 is provided with the radial grooves 304. The spaces between adjacent teeth have at their bottoms the grooves 305, Fig. 8, to receive the wires *b* and the teeth carry the wires forward in the direction of the arrow, Fig. 2, as the carrier is turned, and these spaces are herein referred to as transversely arranged peripheral wire hold-
ers. 4 is a brace fastened to the table 1 and to an upright 44, also fastened to the table, and having the right-angled top portion 44^x to which are fastened the fingers 45 and 142 that extend partly over the carrier and serve 15 to prevent the wires from jumping out of the carrier.

On shaft 52 is mounted a pulley 82 by which the shaft may be driven. It will be understood that the carrier 3 does not turn with the shaft 52, but is mounted loosely thereon and is given a step-by-step motion in any suitable way. One mechanism for giving this step-by-step motion consists of a lever 35 pivoted at 43 to a stand 39 mounted on 20 the table. This lever is provided with a dog 37 pivoted thereto and backed up by a spring 38, the dog engaging the teeth of the carrier one by one as the lever is actuated. The lever extends into the path of movement of 25 a cam 42 turning with the shaft 52, and is provided with a roller 41 in contact with the cam, see Fig. 5.

The groove 301 of the carrier 3 receives a wire hold-down, shown as a band 60, at the 35 right hand side of the machine, see Figs. 1 and 2, which serves to positively hold the wires on the carrier after the wires have been applied to the dauber or swab material and while this material is being cut, as herein-after explained. This hold-down band 60 is supported on a pulley 128 arranged above 40 the carrier and a pulley 140 arranged below the table 1 in a bracket 58, and a band-tightener pulley 61 arranged to the right of the carrier, Figs. 1 and 2, and mounted in a 45 forked slide 6 adjustably arranged on a support 5 mounted on the table 1 and having a back-stop 63. Of course any suitable means 50 may be used for tightening the band or taking up slack therein.

While I prefer to use both the toothed wheel structure and the groove and belt to hold the wires, it is within my invention to dispense with either.

55

The twister head.

21 is a vertically reciprocating rack bar mounted in a bracket 124 supported on a bracket 36 extending from the table. This 60 rack bar is connected with a bar 80 mounted to slide longitudinally in brackets 36 and 123 and engaged by a lever 125 through the medium of a slot and pin connection 125^x or otherwise as necessary or convenient. This lever 65 125 is pivoted at 81 on brackets 65 and 139,

Fig. 3, fastened beneath the table 1. The lever has applied to it or its pivot an arm 17 on which is an adjustable counterweight 16. The other or outer end of the lever is connected with a spring 66 depending from a bracket 29 70 on the bracket 124. The pivot 81 extends over toward the drive pulley 82, and at or near that end has fixed to it an upright arm 92 provided with a roller 95 which is engaged by a cam 96 fast on the shaft 52, so that in 75 the revolution of said shaft the cam will act upon the roller and serve to rock the pivot in its bearing brackets and thereby oscillate the lever 125 against the tension of its spring 66, and consequently move the rack bar up 80 and down in its bearings.

25 is a stand fixed to the bracket 124, and in this stand is stationarily mounted in a bearing 20 a hollow spindle 24 and secured therein as by a set-screw 26. This spindle has 85 a flaring mouth 240 for feeding the sliver or roving or strip which is to be formed into daubers or swabs. This spindle has its end opposite the flaring end provided with a flange 241, and this flanged end is recessed to receive a tubular inset 242 provided with an inclined face flange 243 having a radial slot 244 in its widest part. 245 is a set-screw 90 tapped in the flange 241 and engaging the inset to hold it stationary. On the spindle is mounted a cylinder 22 having a countersunk recess 220 to receive the flanged end of the spindle. This cylinder is provided with a toothed gear 221 which is meshed by the toothed rack bar 21 and thereby given a rotary reciprocating motion on the spindle as an axis or stud-shaft. 28 is a two-diameter or flanged head mounted eccentrically on the cylinder by means of a screw stud 280 and turning thereon and also turning with the 95 cylinder. When a wire handle member *b* is inserted in the slot 244 radially, with its leading end inserted in the tuft-forming material, as shown in Fig. 16, and the cylinder is caused to rotate in the direction indicated by the 100 arrow, Fig. 16, the head 28 sweeps around the inserted wire and bends the end of the wire into a loop which embraces the sliver or roving or other tuft or swab-forming strip and unites the two, as shown in Figs. 110 12 and 18. Because of the functions described 115 the parts shown in detail in Figs. 10 and 11, and 16 to 20, may be appropriately designated a twister head.

120 Referring to Figs. 16 to 20, it will be seen that the high point of the inclined face flange 243 serves as an abutment next to its slot 244 upon which the initial bend of the wire is made and thereafter in the continued rotation of the twister head the wire is coiled 125 about the tuft material, the inclined face of the flange serving to direct the wire in coil form, and this inclined face having its low point immediately in advance of the high point containing the slot. When the coil 130

has been completed the operator sees that the bent wire is freed from the head 28 and slot 244 and the tuft material fed forward to receive another wire, when the operations are repeated.

The bracket 29 may be extended to the left (Fig. 2) and be provided at or near its outer end with a hook-shaped element 75 to afford a support and guide for the sliver, strip 10 or strand of tuft-forming material.

The guide.

It will be understood that the strip or strand of material to be used is inserted into the flared end of the hollow spindle so as to extend out of its opposite end, and the wires applied one by one to the twister head and twisted about the strip at regular intervals, and then engaged by the spring guide fingers 20 31 and 32, the latter longer than the former at their ends nearest the twister head, and curved divergently to facilitate the passage of the product. These fingers are connected by U-shaped clips 33 and similar clips 143, and 25 the fingers are respectively supported upon arms 45 and 142 projecting from portion 44^x, and the stand 34. These fingers are spaced apart sufficiently to permit the passage of the wires and hold them level. In the beginning 30 of the operation the wired strip or strand is hand-fed. As the first formed wire reaches the carrier 3, it drops from the fingers into the teeth of the carrier and thereafter the carrier serves to feed the strip and the attached wires 35 forward until they are caught by the band 60. As the carrier revolves, the wired strip is carried forward beneath its hold-down until the carrier passes from the band 60 and then, 40 the strip having been severed, as will be presently described, the individual daubers or swabs fall from the machine into a suitable receptacle appropriately placed to receive them, and are ready to have the cork and handle elements applied thereto.

45

The clenching mechanism.

As each individual wire is discharged from the guide fingers, it is gripped by a plunger 50, Figs. 2 and 4, normally projected by a spring 51 and the wire is thereby straightened adjacent to its connection with the tuft-forming material. This plunger is carried in the frame 49 mounted on a base 48 and this base is carried by a slide 47 mounted in guides 46 having the face pieces 46^x, and this slide is connected with a yoke 53 mounted on guide rods 68 which project through ears 69 on the yoke and are provided with springs 67 normally tending to elevate 55 the slide. The yoke 53 is provided with a roller 473 which cooperates with a cam 474 fast on the shaft 52. The slide carries a hammer or presser 475 which cooperates with a stationary anvil 476, and as a wire comes 60 opposite these last described elements, the

slide is forcibly moved downward by the cam 474 and the wire thereupon is held by the plunger 50, and then upon a further descent of the slide the hammer or presser 475 strikes a blow upon the wire as it rests on the anvil 476 70 and serves to flatten or compress the loop in the wire and clench it about the strip, as shown in Fig. 13, the spring 51 of the plunger permitting the slide to have this further downward movement without affecting the 75 hold of the plunger on the wire. The adjacent faces of the hammer and anvil may be knurled, toothed or otherwise roughened, as indicated in Fig. 7, to gain a good hold on the article being acted upon.

The anvil 476 is shown as mounted upon brackets 477 on the face pieces 46^x.

The cutter.

When the strip of wired daubers or swabs 85 approach the horizontal center of the carrier they are still in strip form and connected by the dauber or swab forming material. This material has to be cut between adjacent wires in order that each wire may have a quantity 90 of material sufficient to form the head or tuft of the dauber or swab. For this purpose a horizontally arranged circular knife 54, Figs. 4 and 6, is mounted to turn upon a spindle 56 fixed to a slide 70 which is arranged in ways 95 40 on the table or bed plate 1, this slide being normal to the carrier. The slide is provided with a roller 95 which is engaged by a cam 113 on countershaft 114 mounted in bearings 98 and 135 on the table; and this shaft is provided 100 with a bevel gear 93 which meshes with a bevel gear 83 on the shaft 52 and from which said shaft 114 derives rotary motion. As will be understood, the cam gradually 105 moves the slide 70 so that the knife 54 is brought into progressive cutting contact with the dauber or swab material; and in order that the edge of the knife may go clear through this material the radial grooves 304 are provided in the carrier and their adjacent 110 surfaces form abutments against which the material is held as the knife cuts through. The return movement of the slide is automatically effected by the spring 103 made fast to the slide at one end and to some stationary 115 part of the machine at its other end. In order to give to the knife rotary motion, any suitable means may be employed, such as a pulley 541 fast to the knife and engaged by a belt 7 which passes around a pulley 8 on shaft 10 having supports on brackets 9 and 14 through which this shaft 10 extends. On this shaft 10 also is a pulley 12 having a belt 120 13 which connects it with a pulley 11 on a shaft 138. The shafts 10 and 138 may have 125 the bearings 107 and 137. The shaft 138 is provided with a bevel gear 86 in mesh with a bevel gear 116 on a countershaft 115 mounted in bearings 84 and 127 supported on brackets 87 and 134, respectively, projecting from 130

and secured to the frame of the machine. The countershaft has a pulley 85 on its outer end which is connected by a belt 79 with the pulley 80 on the main shaft 52 and from which the parts are driven.

The sharpener.

In order to keep the knife sharp it is preferred to provide emery or other sharpening wheels 108 and 110 in engagement with the upper and lower sides of the cutting edges, at different points as shown, or otherwise. These sharpening wheels may be spring pressed so as to keep them in proper relation to the knife, and they are mounted in suitable brackets 105 and 106 rising from the table or frame.

Thus after the tuft-forming material and the wires are introduced into the machine, the successive operations of connecting the wires and tuft-forming material and the cutting of the material into tufts proceed automatically under the control of the operator. Such control may be effected by treadle 122 connected by a lever 119 pivoted on the frame, and this lever in turn jointed to a lever 120 pivoted on a bracket 121 and connected by a joint 19 with a clutch actuating element 18 having a return spring 141. This clutch is indicated at 102 and is mounted on the shaft 52 and cooperates with pulley 82, and it may be of any well known stop-clutch type.

130 is a bracket upon which is supported a platform or shelf 131 on which is mounted a counter or register 132 operated by the wire handle element.

The invention is susceptible of variations in construction and arrangement, and may be used for making swabs or daubers and the claims following are to be understood accordingly.

What I claim is:

1. A machine for forming swabs, having a tuft and a wire handle element connected therewith, comprising a rotary wire carrier, and means to impart a step-by-step motion thereto, said carrier having transversely arranged peripheral wire holders, means to connect the wires one by one with the tuft-forming material, means to guide the connected elements to the carrier, and means to complete the connection of the wire and tuft forming material while they are supported upon the carrier.

55 2. A machine for forming swabs, having a tuft and a wire handle element connected therewith, comprising a rotary wire carrier, and means to impart a step-by-step motion thereto, said carrier having transversely arranged peripheral wire holders, means to connect the wires one by one with the tuft-forming material, means to guide the connected elements to the carrier, means to complete the connection of the wire and tuft forming material while they are supported

upon the carrier and means to hold the wires in the carrier as they pass beyond the vertical diameter of the carrier.

3. A machine for forming swabs, having a tuft and a wire handle element connected therewith, comprising a rotary wire carrier, and means to impart a step-by-step motion thereto, said carrier having transversely arranged peripheral wire holders, means to guide the connected elements to the carrier, 70 said carrier having a circumferential groove in its rim and a band travelling in said groove and adapted to hold the wires on the carrier, and means to complete the connection of the wire and tuft-forming material 75 while they are supported upon the carrier.

4. A machine for forming swabs, having a tuft and a wire handle element connected therewith, comprising a rotary wire carrier, and means to impart a step-by-step motion 80 thereto, said carrier having toothed flanges serving as wire holders, and means to guide the connected elements to the carrier, and means to complete the connection of the wire and tuft-forming material 85 while they are supported upon the carrier.

5. In a machine for forming swabs having a tuft and a wire handle element, a twister head comprising a hollow stationary spindle provided with a flange at one end, a rotary cylinder mounted on the spindle and recessed to engage the flange on the spindle, the flanged end of the spindle being recessed, a tubular inset mounted in said flanged end 90 stationarily and provided with a radial slot 95 in one side of its outer end and a head axially mounted on the cylinder and turning with it in the vertical plane of the slotted end of the inset.

6. A machine for forming swabs having 105 a tuft and a wire handle element, comprising a wire carrier and means to impart step-by-step motion thereto, said carrier having transversely arranged peripheral wire holders, means to connect the wires one by one with 110 the tuft-forming material, means to guide the thus connected elements to the carrier, an anvil and a reciprocating hammer arranged adjacent to the carrier to clinch the connection between the wire and the tuft-forming material.

7. A machine for forming swabs having a tuft and a wire handle element, comprising a wire carrier and means to impart step-by-step motion thereto, said carrier having transversely arranged peripheral wire holders, means to connect the wires one by one with the tuft-forming material, means to guide the thus connected elements to the carrier, 120 an anvil and a reciprocating hammer arranged adjacent to the carrier to clinch the connection between the wire and the tuft-forming material, and means to straighten the wire adjacent to its connection with the tuft-forming material.

8. A machine for forming swabs having a tuft and a wire handle element, comprising a wire carrier and means to impart step-by-step motion thereto, said carrier having transversely arranged peripheral wire holders, means to connect the wires one by one with the tuft-forming material, means to guide the thus connected elements to the carrier, and means to clinch the wires one by one on the tuft-forming material which comprises a stationary anvil, a hammer, positive means to actuate the hammer in one direction and automatic means to effect the return movement of the hammer.
- 15 9. A machine for forming swabs having a tuft and a wire handle element, provided with a rotary wire carrier and means to impart a step-by-step rotation thereto, said carrier having transversely arranged peripheral wire holders, means to connect the wires one by one with tuft-forming material, means to guide the wires thus attached to the tuft-forming material to the carrier, and means to sever the tuft-forming material between adjacent wires, said carrier having radial grooves in its face adjacent to the severing means to permit the passing of the severing means through the tuft-forming material.
- 20 10. A machine for forming swabs having a tuft and a wire handle element, provided

with a rotary wire carrier and means to impart a step-by-step rotation thereto, said carrier having transversely arranged peripheral wire holders, means to connect the wires one by one with tuft-forming material, means to guide to the carrier the wires thus attached to the tuft-forming material, and a rotary knife arranged to one side of the vertical diameter of the carrier and adapted to cut the tuft-forming material between adjacent wires.

11. In a machine for forming swabs having a tuft and a wire handle element, a rotary wire carrier and means to impart a step-by-step rotation thereto, said carrier having transversely arranged peripheral wire holders, means to connect the wires one by one with tuft-forming material, means to guide to the carrier the wires thus attached to the tuft-forming material, a rotary knife arranged to one side of the vertical diameter of the carrier and adapted to cut the tuft-forming material between adjacent wires, and means cooperating with the carrier to positively hold the wires and tuft-forming material engaged thereby while the tuft-forming material is being cut.

In testimony whereof I have hereunto set my hand this 22d day of January, A. D. 1923.

PETER CODINA.
